UNITED STATES PATENT OFFICE.

JAMES W. HILLIKER, OF TRAVERSE CITY, MICHIGAN:

HEATING-DRUM.

SPECIFICATION forming part of Letters Patent No. 653,676, dated July 17, 1900.

Application filed December 15, 1899. Serial No. 740,434. (No model.)

To all whom it may concern:

Be it known that I, JAMES W. HILLIKER, a citizen of the United States, residing at Traverse City, in the county of Grand Traverse 5 and State of Michigan, have invented a new and useful Heating-Drum, of which the following is a specification.

This invention relates to heating-drums, the object in view being to provide an efficient 10 drum of simple construction which may be applied to the stovepipe of any ordinary heater, the drum by reason of its particular construction greatly economizing fuel and heat and securing a greater radiation of heat than is 15 possible with the ordinary stovepipe.

It is also an object of this invention to provide an intermediate flue of novel shape which is also adjustably mounted and which will cause the products of combustion to pass back 20 and forth lengthwise of the drum and also to combine with the drum a centrally-arranged cold-air duct in which air may be heated and conveyed to any desired point, the cold air being supplied to said duct either from above 25 or beneath the drum and either from the room in which the heater is located or from an overhead or an adjoining room.

The detailed objects and advantages of the invention will appear in the course of the ensuing description.

The invention consists in a heating-drum of novel construction and other novel features and details of construction and arrangements of parts, as hereinafter fully described, 35 illustrated in the drawings, and incorporated in the claims.

In the accompanying drawings, Figure 1 is a vertical sectional view of a drum constructed in accordance with the present invention 40 shown applied to a heater and stovepipe and showing also the association with the heater of a cold-air duct. Fig. 2 is a similar view showing a different arrangement of cold-air duct. Fig. 3 is an enlarged detail vertical 45 section through the upper portion of the drum, taken at right angles to Figs. 1 and 2. Fig. 4 is a horizontal cross-section through the lower portion of Fig. 3.

Similar numerals of reference designate corresponding parts in all the figures of the drawings.

In order to illustrate the application of the

present improvements, I have shown in Figs. 1 and 2 an ordinary heating-stove 1, a stovepipe 2 for conveying therefrom the products 55 of combustion, and a chimney-breast 3, which is pierced by the upper portion or elbow 4 of the stovepipe.

The drum contemplated in this invention and indicated at 5 is conico-cylindrical in 60 shape, being largest at its lower end and smallest at its upper end, the said drum tapering regularly from its lower end toward its upper end. The drum is preferably composed of sheet metal and comprises, essentially, an 65 outer wall 6, the lower end of which is partially closed by a conical bottom 7, which forms the seat for the intermediate flue, hereinafter described. The bottom 7 is provided with a pendent flange 8, by means of which 70 it may be coupled to the lower section of the stovepipe 2, as clearly shown in Figs. 1 and 2. The upper end of the drum is partially closed by means of a conical top 9, which has an upwardly-projecting flange 10 to enable 75 the superimposed section of the stovepipe 2 to be coupled to the drum.

Within the drum and extending lengthwise thereof is a centrally-arranged cold-air duct 11, which is stationary with respect to the 80 drum and stovepipe. The cold-air duct enters the drum at the bottom, passes entirely therethrough, and out through the top of the drum into the superimposed section of the stovepipe, where it is provided with an elbow 85 or bend 12, which communicates with an outlet-port 13 in the stovepipe. Said cold-air duct 11 is also provided below the drum with another elbow 14, which passes outward through an opening 15 in the stovepipe, whence 90 it is extended downward alongside the heater to provide a terminal portion 16, which is preferably extended to a point adjacent to the floor of the room in which the heater is located, the lower end of said cold-air duct being 95 reticulated or provided with inlet-openings 17 for the admission of air to the duct. The cold air entering the bottom of the duct 11 passes upward centrally through the heater and is heated and allowed to escape through 100 the port 13 into the same room in which the heater is located.

In lieu of the arrangement of cold-air duct just described, the initial or terminal portion

- 16 of said duct may communicate with an adjoining or overhead room, as shown in Fig. 2, and the discharge end of said cold-air duct may also be passed into said adjoining room, 5 as illustrated in the same figure, an essential feature of the arrangement being that a portion of said duct must pass centrally through and lengthwise of the drum. Under either arrangement a spiral deflector 18 is fixedly 10 mounted within the cold-air duct or that portion which lies within the drum, so as to retard the upward movement of the column of air being heated, thereby subjecting it to a more thorough heating.
- 15 Within the drum 5 and between the outer wall 6 thereof and the centrally-arranged cold-air duct 11 is interposed an intermediate flue 19, comprising an inner flue-wall 20 and an outer flue-wall 21. The two walls 20 and 21 20 are rigidly connected by means of suitable bolts, rivets, or equivalent connections 22, sufficient space being left between the walls 20 and 21 to permit the products of combustion to pass lengthwise of the drum. Both 25 the inner and outer flue-walls 20 and 21 are of conicocylindrical shape, the object in making the walls 6, 20, and 21 of said shape being to cause the products of combustion to impinge against and follow along said walls 30 in moving back and forth in the several flues. It will thus be seen that in addition to the intermediate flue 19 an outer flue 23 is provided outside of the outer flue-wall 21 and an inner flue 24 between the inner wall of the intermediate flue and the centrally-arranged cold-air duct. 35
- The bottom edge of the inner flue-wall 20 is adapted under one adjustment of the intermediate flue to rest upon the conical seat 7, 40 formed by the bottom of the drum, while the bottom edge of the outer flue-wall 21 terminates above said seat in order to allow the products of combustion that pass down through the intermediate flue to pass around 45 the bottom edge of said wall and upward through the outer flue 23. On the other hand, the outer flue-wall 21 extends above the inner wall 20, so as to allow the products of combustion moving upward through the inner flue 50 to pass over the upper edge of the inner wall 20 and downward through the intermediate flue. A crown-plate 25 is connected with the upper edge of the outer flue-wall 21 and is provided with a central opening 26, in which 55 is received an upwardly-tapering conical centering device 27, preferably mounted upon the air-duct 11 as a convenient means of support. I also provide an annular ledge 28, which for convenience is formed integrally 60 with the centering device 27 and supported therewith upon the cold-air duct 11. The intermediate flue comprised by the inner and outer walls 20 and 21, respectively, is adapted to be raised and lowered. As it is raised the 65 crown-plate 25 is carried upward above the ledge 28, so as to allow the products of combustion to pass directly from the inner flue

into the superimposed section of the stove-pipe. As the intermediate flue is lowered, the conical centering device 27 and the conical seat 7 at the bottom of the drum both act to center the intermediate flue and cause it to assume its proper position within the drum. When the intermediate flue is lowered, the crown-plate 25 rests upon the annular ledge 28 and shuts off the direct passage between the inner flue 24 and the overlying stovepipe, thereby causing the products of combustion to pass downward through the intermediate flue and upward through the outer flue and thence in the pipe. 70

In order to raise and lower or adjust the intermediate flue, a lifting-bail 29 is connected permanently to the crown-plate 25, extending thence upward over the cold-air 75 duct 11, where it is pivotally connected to one end of a lever 30, fulcrumed intermediate its ends and having connected to its opposite end an operating device 31, which is arranged exteriorly of the pipe and drum and provided 80 with one or more catch-shoulders 32, adapted to engage with a stop-shoulder 23 on the drum for the purpose of sustaining the intermediate flue in an elevated position or with its lower edge out of contact with the seat or bottom 7 95 of the drum and its crown-plate out of contact with the annular ledge 28.

By providing the drum with a conicocylindrical outer wall and constructing the intermediate flue with walls of corresponding 100 shape the productions of combustion are caused to impinge against all of the walls, thereby producing a greater radiation of heat. In view of the fact that the inner flue-wall 20 converges toward the cold-air duct as it approaches the upper end of the drum the products of combustion are also caused to follow 105 closely and impinge against said air-duct. By making the intermediate flue adjustable vertically it is possible to cause the products 110 of combustion to pass either directly through the inner flue upward into the stovepipe or deflect them and cause them after reaching a point adjacent to the upper end of the drum to pass downward through the intermediate 115 flue and again upward through the outer flue and thence to the upper sections of the stovepipe. The adjustment of the intermediate flue is effected by simple means, and the cold air which passes through the duct 11 may be 120 taken either from the room in which the heater is located or from an adjoining room and may be delivered into the same room with the heater or into an adjoining room, as occasion demands. The passage of the cold 125 air through the cold-air duct is also considerably retarded, and by the arrangement as a whole the air passing through the centrally-arranged duct is not only delivered at a higher temperature, but a more effective radiation of 130 the heat from the drum is at the same time obtained.

From the foregoing it is thought that the construction, operation, and many advan-

tages of the herein-described invention will be apparent to those skilled in the art without further description, and it will be understood that various changes in the size, shape,

5 proportion, and minor details of construction may be resorted to without departing from the spirit or sacrificing any of the advantages of the invention.

Having thus described the invention, what 10 is claimed, and desired to be secured by Letters Patent, is—

1. The combination with a drum, of a centrally-arranged cold-air flue, and a double-walled flue arranged within the drum and 15 surrounding the cold-air flue to form the inner and outer flues, said double walls forming between themselves an intermediate flue which communicates at its opposite ends with the inner and outer flues.

20 2. The combination with a heating-drum having inner and outer flues, of a double-walled downdraft-flue arranged within the drum and having its flue-passage communicating at its upper and lower ends, respectively, with the inner and outer flues, and means for adjusting said downdraft-flue.

30 3. The combination with a drum, of an inner cold-air flue, a double-walled flue within the drum and surrounding the cold-air flue to form therewith the inner and outer flues, said double walls forming between themselves an intermediate flue which communicates at its opposite ends with the inner and outer flues, and means for adjusting the double-walled 35 flue vertically to seat and unseat the same within the drum.

40 4. The combination with a heating-drum, of a double-walled flue arranged within the drum and forming therein the inner and outer updraft-flues, said double walls forming between themselves an intermediate downdraft-flue which communicates at its opposite ends with the inner and outer flues, respectively, a seat on the drum for the lower end of one 45 wall of said downdraft-flue, another fixed seat within the drum for the upper end of the other wall of said flue, and means for adjusting the flue to and from the seats and thereby establish a direct or indirect draft 50 through the structure.

5. The combination with a heating-drum, of a centrally-arranged cold-air duct extending lengthwise therethrough and fixed with relation to the drum, connected flue-shells surrounding the air-duct and interposed between the latter and the outer wall of the drum, said connected shells forming between themselves an intermediate return-flue, and means for adjusting the shells, substantially as de- 55 scribed.

6. The combination with a heating-drum, of a centrally-arranged cold-air duct mounted fixedly therein, a stationary spiral deflector arranged within said duct, and the adjustable 60 flue-shells surrounding the cold-air duct and forming between themselves an intermediate

down-flue which communicates at its opposite ends with up-flues around the cold-air duct and the drum-shell, substantially as specified.

7. A heating-drum comprising a tapering shell, and a return-flue having connected tapering shells forming between themselves a flue-passage and said flue arranged concentric in the drum-shell to form therein the inner and outer flues with which the flue-passage of the double-shelled flue communicates at opposite ends, and means for adjusting the return-flue bodily in the drum-shell to establish a direct or indirect draft therethrough.

8. The combination of a drum having a seat at its lower part, a cold-air flue, another seat on said flue, a double-walled return-flue surrounding the cold-air flue and having its respective walls adapted to the seats, and means for adjusting the return-flue bodily within the drum, substantially as described.

9. The combination of a drum, a cold-air flue therein, a conical seat on the cold-air flue, a double-walled return-flue provided at one end with a crown-plate fitted slidably to the conical seat, and means for adjusting the return-flue bodily within the drum, substantially as described.

10. In a heating-drum, a double-walled return-flue having the inner wall extended at one end beyond the companion wall, and a crown-plate fixed to the last-named wall, combined with a drum-shell, a central flue, a guide fixed on said central flue and provided with a seat on which the crown-plate is adapted to rest, and means for adjusting the return-flue.

11. The combination with a heating-drum, of a central flue extending therethrough, a seat on the flue, a double-walled return-flue arranged within the drum and surrounding the central flue, a crown-plate fast with one wall of the return-flue and adapted to the seat on the central flue, a bail spanning the central flue and connected to the double-walled flue, a lever connected to the bail, and an adjusting device for the lever, substantially as described.

12. The combination with a heating-drum, of a central cold-air flue, and a conical cylindrical flue surrounding the cold-air flue and arranged within said drum, the inner and outer walls of said flue being concentric and forming between themselves a return-flue passage, substantially as and for the purpose specified.

13. The combination with a heating-drum, of an interiorly-arranged double-walled flue, the inner wall of said flue extending below the outer wall, and the outer wall extending above the inner wall, a crown-plate at the top of the outer wall, and a ledge on which said crown-plate rests.

14. The combination with a heating-drum having a conical bottom forming a flue-seat, of an interiorly-arranged adjustable double-

walled flue, the inner wall of which extends below the outer wall and rests on said seat, the outer wall of said flue extending above the inner wall, a crown-plate at the top of the 5 outer wall, and a ledge on which said crown-plate is adapted to seat itself, substantially as specified.

In testimony that I claim the foregoing as my own I have hereto affixed my signature in the presence of two witnesses.

JAMES W. HILLIKER.
